UNITED STATES PATENT OFFICE.

WILLIAM H. CLOUD, OF DETROIT, MICHIGAN, ASSIGNOR, BY MESNE ASSIGNMENTS, OF ONE-HALF TO WM. H. JACKSON, OF SAME PLACE.

LIFTING AND FORCE PUMP.

SPECIFICATION forming part of Letters Patent No. 257,473, dated May 9, 1882.

Application filed April 21, 1881. Renewed April 8, 1882. (No model.)

To all whom it may concern:

Be it known that I, WILLIAM H. CLOUD, of Detroit, in the county of Wayne and State of Michigan, have invented an Improvement in 5 Lifting and Force Pumps, of which the following is a specification.

The nature of my invention relates to certain new and useful improvements in that class of pumps known as "force-pumps;" and the invention consists in the construction and arrangement of parts, as more fully hereinafter described.

Figure 1 is a vertical central longitudinal section. Fig. 2 is a plan with the top and upper valve-chamber removed. Fig. 3 is a vertical central cross-section on the line *x*-*x* in Fig. 2. Fig. 4 is a top plan.

In the accompanying drawings, which form a part of this specification, A represents a pump-barrel of nearly rectangular form, open on the top side, and provided with valves *a* and *b*, seated in the bottom of said barrel. By the means of these valves and openings upon which they are seated a communication is had 25 between said barrel and a water-way, B, in the base of the pump, and into which water is admitted through the suction-pipe C. The pump-barrel at one end is cast with an annular flange, *c*, to which is bolted a head, *d*, with which is engaged a plug and stuffing-box, *e*, through which the piston-rod D has its reciprocating motion, as in the ordinary construction of steam-engines. The opposite end of this barrel is cast solid, as shown, in which particular it differs 35 from other pumps of a similar character, which are provided with a removable head, by means of which access is obtained to the interior of the barrel at that end. This barrel is also provided with a diaphragm, E, through the center

40 of which is a round hole, into which is fitted a stuffing-box, F, through which the hollow piston G, which is secured to the piston-rod D, has a reciprocating motion. This diaphragm divides the barrel into two chambers, H and H', between which there is no communication when the piston and its stuffing-box is in place. It will be noticed that the piston is a shell, and it is designed, in order not to wear the stuffing-box unequally, that its weight shall be about 45 equal to the weight of water which it would

displace, and that the ends of this piston are beveled to enable it to be forced with less power than though the ends were flat. Channels *h* may be cut around the inner face of the stuffing-box F to provide for a water packing of 55 the piston, thereby enabling the pump to be used with hot water, which could not be done were rubber or other elastic rings employed for the purpose.

5 Is a water-chamber and valve-chamber combined, with openings *i* *i'* in its bottom opening into the pump-barrel, of which said water and valve chamber forms a cap. *k* *k'* are the valves which alternately close and disclose the openings *i* *i'*. There are other openings, *m* *m'*, in 60 the bottom of this chamber communicating with the exit-openings *n* *n'*, one of each being on either side of the trunk, and to either of which may be attached a suitable pipe or hose. If a constant flow of water is desired, one of 65 these exit-openings should be closed by a plug, as shown.

70 J is a cap or cover to the valve-chamber, surrounded by the air-chamber L, of the usual construction. The joints between the pump-barrel A and the valve-chamber I and between the latter and the cap J should be perfectly tight, preferably being so made by grinding.

75 The inlet-pipe C being put into communication with a proper water-supply, when the piston is reciprocated the water is drawn alternately through the valves *a* *b* and forced alternately through the valves *k* *k'* into the chamber I, and thence through the outlet *n*. 80

85 The piston-rod D is designed to be connected with the piston-rod of a reciprocating engine of sufficient length of stroke to actuate the piston of the pump.

90 Cast upon the sides of the pump-barrel are ears *o*, to which are pivoted one end of the bolts *s*, the opposite ends of which are threaded and provided with a nut, *t*, and the edges of the cap J are provided with similar slotted ears, *o'*, and the bolts *s* are of the proper length, so 95 that when the cap is in place the free ends of the bolts are engaged with the ears of the cap, as shown in Fig. 4, when the nuts *t* are tightened to hold the parts rigidly together. To remove the cap it will be noticed it is not nec- 100

essary to remove a bolt, but simply loosen the nuts and slide the upper ends of the bolts out of engagement with the ears in the caps.

It will further be noticed that by removing 5 the cap J and the valve-chamber I access can be had to all parts and both chambers of the pump-barrel without the necessity of removing the heads of the barrel as such are ordinarily constructed.

10 What I claim as my invention is—

1. In a pump, the barrel A, divided into two chambers, H H', by a diaphragm, E, through which the piston reciprocates, in combination with a removable top closing the upper openings of the chambers H H', whereby access can be had to the inlet-valves in each of said chambers without removing either head of the barrel, substantially as described.

2. In a pump, the barrel A, provided with 20 a diaphragm, E, forming two chambers, H H', in combination with a removable top closing the upper openings of said chambers, a stuffing-box secured in the diaphragm E, and the piston G, substantially as and for the purpose 25 specified.

3. In a pump, the combination of the pump-barrel, diaphragm, and piston, constructed substantially as described, with the separable exit-valve chamber or box I and separable cap J, surmounted with the air-chamber L, whereby 30 access can be had either to the exit-valves, the barrel, or the inlet-valves without removing either head of the barrel, substantially as specified.

4. The pump-barrel A, divided into separate 35 chambers H H' by a diaphragm, E, in combination with the separable exit-valve chamber I, closing the upper openings of the chambers H H', the separable cap J, closing the valve-chamber I, and bolts s s, pivoted between lugs 40 o o of the barrel A, and engaging with lugs o o of the cap for detachably securing the barrel A, chamber I, and cap J together, substantially as and for the purpose described.

WILLIAM H. CLOUD.
